Attorneys.

UNITED STATES PATENT OFFICE

JAMES H. REED, OF SWAMPSCOTT, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY

PRESSER-FOOT MECHANISM FOR SEWING MACHINES

Original application filed November 11, 1922, Serial No. 600,224. Divided and this application filed October 20, 1923. Serial No. 669,829.

This invention relates to presser-foot mechanism and especially, although not exclusively, to presser-foot mechanism for lock stitch shoe sewing machines of the general type shown in Patent No. 1,482,619 dated February 5, 1924, and in my prior application for Letters Patent, Serial No. 542,666, filed March 10, 1922, on which Patent No. 1,688,056 issued October 16, 1928, the present application being a division of application Serial No. 600,224, filed November 11, 1922, on which Patent No. 1,706,743 issued March 26, 1929.

This invention has for its object to provide improved presser-foot operating means of such a character as to insure the lifting of the presser-foot a constant distance above the work irrespective of the thickness of the latter.

20 This and other objects of the invention, together with means whereby the same may be carried into effect, will best be understood from the following description of a preferred embodiment thereof illustrated in the accompanying drawings, in which—

Fig. 1 is a front elevation of the upper part of the sewing machine.

Fig. 2 is a vertical section taken substantially on the line 2—2, Fig. 1.

30 The invention is herein illustrated as embodied in a machine of the type described in my prior application above referred to. Said machine is adapted primarily for sewing shoes of the McKay type, but is also capable of use for many other purposes, as, for example, for stitching along the shanks on the inside of shoes of the Goodyear welt type. The machine sews a lock-stitch seam and has a straight, flattened, hooked needle 15 and a shuttle 16 supplying a shuttle thread on the outer side of the sole of the shoe or other work W, while within the shoe, or at the opposite side of said work, there is a cooperating work-supporting horn 17 having in its

tip an oscillating looper or whirl 18 supplying a cop or needle thread.

The needle 15 is carried by a needle bar 19 which is connected by a link 20 with a lever 21 pivoted in the head frame 22 and operated by a cam 23 on the main shaft 24 journalled in said head frame 22 and adapted to receive power from any suitable source.

The shuttle 16 is of the discodial type and is mounted in a shuttle race 27 supported at 55 the bottom of the head frame 22 in a position to hold the shuttle with its front face slightly inclined to the path of the needle. The shuttle has a hook 28 projecting from its front face and extending circumferentially thereof, the arrangement being such that, as the shuttle is oscillated, said hook will cross the path of the needle, take the loop therefrom, and cast the same over the shuttle, said hook passing at one side of the path of the needle 60 when in its uppermost position.

The whirl 18 is oscillated, by mechanism not shown herein, to place a loop of cop thread in the open hook of the needle 15 when the latter is in its lowermost position, said 70 loop being taken from the needle, when the latter rises, by the shuttle 16, and the shuttle thread being passed therethrough, as above explained.

Between the formation of successive 75 stitches, the work is fed forwardly by means of a four-motion feed point or awl 42.

The parts thus far referred to, except as they enter into combination with the parts hereinafter described, specifically form no 80 portion of the present invention and may be of any suitable construction and arrangement. They will, therefore, not be further discussed herein, as they are fully shown and described in my prior application above referred to, and the foregoing explanation of their nature and function will be sufficient for a complete understanding of the invention about to be described.

The work W is, during the stitch-forming 90

operations, clamped upon the work-supporting horn 17 by a presser-foot 34 carried by a presser-foot bar 35 guided for vertical movement in the head frame 22. Said presser foot is pressed toward the work by a torsion spring 36 carried by a rod 37 supported at its ends in brackets 38 and 39 secured to the top of the head frame 22, said spring engaging at one end a stud 40 carried by the presser-foot bar 35. In order to permit the work to be fed, the presser-foot is periodically lifted by mechanism comprising a slide 43 on the presser-foot bar 35, said slide carrying a pivoted pinch dog 44 which is engaged by a bell crank lever 45 pivoted to the head frame 22 and having a roller which cooperates with a cam surface on the cam 23. The arrangement is such that, when the dog 44 is raised by the lever 45, it will first turn upon its pivot to engage the presser foot bar 35 with a clamping pressure, the slide 43 being then lifted by the lever 45, acting through the dog 44, and carrying with it the presser foot bar. As the dog 44 is released by the lever 45, it will, in turn, release the presser-foot bar 35, permitting the spring 36 to depress the latter, the slide 43 being independently depressed by a spring 46 to an extent determined by the engagement of an adjusting screw 47 carried by said slide with an adjacent portion of the head frame 22. The stroke of the lever 45 being constant, it will be seen that the movement imparted to the slide 43 will depend upon the adjustment of the screw 47, being, however, constant in amount for each adjustment of said screw. The slide 43 and dog 44 constitute an intermittent grip device which cooperates with the presser-foot bar 35 to lift the latter a predetermined amount, irrespective of the initial position of said bar, this amount being equal to the amount of movement of said slide 43. It will, therefore, be seen that, irrespective of the thickness of the work W, the presser-foot 34 will at each operation of the machine be lifted the same distance above the upper surface of the work, this amount being determined by adjustment of the screw 47.

50 The presser-foot may be lifted by the operator in order to permit the insertion or removal of the work by means of a lever 48 fulcrumed upon the bracket 39 and engaging at its forward end an opening in the presser-foot bar 35, said lever being operated through suitable connections by a treadle (not shown) at the base of the machine.

Having thus described my invention, I claim:

60 In a sewing machine, in combination, a work support, a head frame, an operating shaft journalled in said frame; a presser-foot bar guided in said frame; a presser-foot carried thereby and cooperating with said work support, a slide guided on said presser-

foot bar, a pinch dog pivoted to said slide and adapted to frictionally engage said presser-foot bar with a clamping pressure, a lever fulcrumed in said frame and arranged directly to engage said dog to lift said slide through said dog and to cause said dog to engage said presser-foot bar, a cam on said shaft directly engaging said lever for operating said lever, and a spring for depressing said presser-foot bar when released by said dog.

In testimony whereof I affix my signature.
JAMES H. REED.
